UNITED STATES PATENT OFFICE.

KING C. GILLETTE, OF BROOKLINE, MASSACHUSETTS.

SAFETY-RAZOR.

1,158,481.

Specification of Letters Patent.

Patented Nov. 2, 1915.

Application filed January 23, 1911. Serial No. 604,073.

To all whom it may concern:

Be it known that I, KING C. GILLETTE, a citizen of the United States, and a resident of Brookline, in the county of Norfolk and State of Massachusetts, have invented certain new and useful Improvements in Safety-Razors, of which the following is a specification.

This invention relates to safety razors of the detachable-blade type, and resides in certain features of construction and arrangement which are hereinafter set forth and which have to do more particularly with the parts which compose the blade-holding and handle portion of the razor.

In the accompanying drawings, Figure 1 is a side elevation of a razor embodying my improvements, as preferably constructed; Fig. 2 is a similar view, showing the head of the razor in central section from front to back; Fig. 3 is a rear elevation of the head of the razor; Fig. 4 is a sectional plan view of the same, following the line $\alpha-\alpha$ in Fig. 3; Figs. 5, 6 and 7 are views similar to Figs. 1, 2 and 3 respectively, illustrating a modification; and Fig. 8 is a top plan view of the parts shown in Fig. 7.

In the form of razor shown in Figs. 1 to 4 inclusive, the holder comprises a handle 2, a head 3 attached to one end of the handle, and a detachable blade 4 which preferably has but a single cutting edge and is provided along its opposite edge with a reinforcing strip 5. The front edge of the head 3 is provided with a guard such as a line of teeth 6 of suitable form, and with stops preferably consisting of upwardly-projecting lugs 7 located at the opposite ends of the line of guard-teeth 6 for engaging the cutting edge of the blade at its ends and holding said edge in operative position, at the same time covering the corners thereof. The blade 4 is positioned in an endwise direction by means of lugs 8 extending upward from the head 3 and located at such a distance apart that the adjacent portion of the blade will drop freely between them, and said blade is supported at its rear edge and also pressed forward against the stops 7 by means of a combined support and back clamp located at or near the rear edge of the head and mounted to have a rocking movement by virtue of which it may be operated to release the blade or caused to engage the same and hold it in operative relation with the head 3. This back clamp, as

illustrated in Figs. 1 to 4 inclusive, is formed from a strip of metal 9 passing through a slot 10 in the head 3 and mounted to rock therein, the lower portion of said strip being bent upon itself to provide an actuating spring 11 which bears at its upper end against the handle 2 and tends to throw the upper end of the strip forward. At its upper end said strip 9 is provided with prongs 65 bent to form jaws which receive the rear edge of the blade 4 between them and provide a support therefor as well as a clamp for pressing the blade forward and holding its cutting edge against the stops 7. The 70 prongs above referred to are preferably three in number, and according to the arrangement shown in Figs. 2 and 3 the middle prong 12 is bent forward and downward to support the rear edge of the blade at its 75 center, while the other two prongs 13 extend slightly above the rear edge of the blade, in position to press downward as well as forward thereon and thus hold the blade upon the supporting prong 12.

The strip 9 is held in place and permitted to rock in the head 3 by virtue of notches 14 provided at its edges, the slot 10 having a shorter extension at its rear which receives the strip 9 between the inner ends of the 85 notches 14 somewhat loosely. This position of the strip is maintained by means of the spring 11, which presses the strip rearward, the upper portion of said strip being held in fixed position by the engagement of the 90 prongs 13 with the blade 4 when the latter is inserted and by the engagement of the free end of the prong 12 with the top of the head 3 when the blade is removed. These parts are so proportioned that when the 95 blade is in position in the holder the prong 12 will be lifted slightly out of contact with the top of the head 3, so that the prongs 13 must necessarily press upon the rear edge of the blade. The slot 10 is made large 100 enough to permit the doubled lower portion of the strip 9 to be inserted through it from the upper side of the head 3 until the free end of the spring 11 passes below the head and the notches 14 are brought opposite the 105 rear extension of said slot, whereupon the strip will spring into the position above described.

In the modification shown in Figs. 5 to 8 inclusive, the combined support and back clamp for the blade is of slightly different shape and comprises a transversely-extend-

ing bar 9' which is pivoted at its ends in the upstanding lugs 8 and thus provides for the rocking movements above described. This form of the combined support and back-
5 clamp, like the one first described, is pref-
erably made of sheet metal and operates in
the same way. It is shown in Figs. 6 and
7 as having its middle prong 12' extending
upward and forward to press upon the
10 rear edge of the blade, its other two prongs
13' being bent downward to support the
rear edge of the blade and form stops to
limit the rocking movement of the clamp
when the blade is removed, but the number,
15 arrangement and relative location of the
prongs may be varied, if desired. Either
of the arrangements above described, how-
ever, has the advantage that the engage-
ment of the front edge of the blade at its
20 ends and the rear edge of the blade at its
center or thereabouts provides a three-point
bearing for the blade, so that said blade
is firmly held in exact position without pos-
sibility of rocking or remaining out of con-
25 tact with any of the blade-engaging devices.

The lower portion of the back clamp, be-
ing located near the upper end of the handle
and in the rear of the same, is in convenient
position to be engaged and pressed upon by
30 the thumb of the user for lifting the up-
wardly-extending clamping prong or prongs
to permit the insertion or removal of a
blade, and the construction above described
is also advantageous for the reason that it
35 enables the holder to be produced at slight
expense, since each part of the holder except
the handle may be made from a single piece
of sheet metal and quickly and easily as-
sembled with the other parts, while the han-
40 dle may be made from a metal rod and
readily produced by automatic machines of
a well-known type. Furthermore, the parts
of the head 3 are of open construction and
therefore easily kept clean, while the fact
45 that the holder has but one movable part
and no adjustments makes it very durable

and not likely to get out of order. The de-
scribed construction also provides for in-
serting the blade without having to slide it
under overlying parts or otherwise moving
it in any manner which might cause its cut-
ting edge to be dulled by contact with any
part of the holder; all of which advantages
contribute to the practical utility of the ra-
50 zor, as will be evident. 55

I claim as my invention:—

1. In a safety razor, a holder comprising
a handle, a head having a guard and stops
for positioning the cutting edge of the blade
with respect to the same, a spring-actuated 60
blade-clamping device constituting a sepa-
rate member from the head and mounted to
rock toward and away from said stops, said
device being provided above the head with
means for pressing forwardly against the 65
rear edge of the blade to hold the latter
against the stops and also with means ar-
ranged to extend beneath and support the
rear portion of the blade when unclamped,
leaving said blade free to be lifted upward 70
from the head, and lugs for positioning the
ends of the blade and providing an up-
wardly-unobstructed space for the reception
and removal of the same.

2. In a safety razor, a holder comprising 75
a handle, a head having a guard and stops
for positioning the cutting edge of the blade
with respect to the same, said head being
provided at its rear portion with a trans-
versely-extending slot having a wider and 80
a narrower portion, and a combined blade
support and back clamp of such width as
to pass through the wider portion of the
slot and notched to enter and take a pivotal
bearing in the narrower portion of said slot. 85

In testimony whereof, I have hereunto
subscribed my name this twentieth day of
January, 1911.

KING C. GILLETTE.
